RODENT PROTECTIVE BOTTOM SHIELD FOR TELEPHONE PEDESTAL

Arthur Everett Forseth, Halstad, Minn. 56548

Filed Jan. 27, 1972, Ser. No. 221,478

Term of patent 14 years

Int. Cl. D8—08

U.S. Cl. D8—263

FIG. 1

FIG. 2

FIG. 3

FIG. 4

FIG. 1 is a perspective view of a rodent protective bottom shield for telephone pedestal showing my new design;

FIG. 2 is a side elevational view thereof;

FIG. 3 is a top plan view thereof;

FIG. 4 is a bottom plan view thereof.

I claim:

The ornamental design for a rodent protective bottom shield for telephone pedestal, as shown.
